UNITED STATES PATENT OFFICE.

ELBERT D. HALE, OF ROGERS, ARKANSAS.

MONEY-CHANGING MACHINE.

No. 842,885.

Specification of Letters Patent.

Patented Feb. 5, 1907.

Application filed September 11, 1905. Serial No. 277,962.

To all whom it may concern:

Be it known that I, ELBERT D. HALE, a citizen of the United States, residing at Rogers, in the county of Benton and State of Arkansas, have invented certain new and useful Improvements in Money-Changing Machines, of which the following is a specification.

My invention contemplates certain improvements in money-changing apparatus of that class in which the desired coin is ejected in a chute by simply pressing down a key-lever with the proper denomination designated thereon.

15 The object of the invention is to provide a device of this character which may be used not only for the purpose of ejecting a coin or any number of coins for the purpose of making change, but which may also be used for 20 the purpose subtracting coins when a sale has been made, so that all annoyance arising from mental calculations is avoided, the apparatus automatically making the desired subtraction, so as to obtain the proper change, 25 it being only necessary for the operator to press down the key of the proper denomination designating the selling cost of the article.

With these and other objects in view the 30 invention consists in a novel mechanism whereby the actuation of the coin-ejecting devices may be readily effected, and also consists in certain detail arrangements and construction of the parts, as will be described 35 more fully hereinafter, and pointed out in the claims.

For a full description of the invention and the merits thereof and also to acquire a knowledge of the details of construction of 40 the means for effecting the result, reference is to be had to the following description and accompanying drawings, in which—

Figure 1 is a face or front view of my improved money-changing apparatus with the 45 cover removed. Fig. 2 is a longitudinal section thereof. Fig. 3 is a detail perspective view illustrating one series of superposed coin-ejecting slides, the slides being spaced from each other for the purposes of illustration only, as in practice they lie directly one upon the other.

Referring to the drawings, 1 designates a suitable casing provided with a base 2, underneath which is a chute 3, designed to convey the desired coins into any receptacle, such as a tray 4. Mounted on the base 2 is a

predetermined number of cylindrical coin-cups 5, which are alike in construction except that they vary in diameter according to the diameter of the coins which they are intended to accommodate. At the bottom of each coin-cup is located a predetermined number of coin-ejecting plates 6, each of which is of approximate thickness equal to the width of the coins it is intended to eject and each of 65 which is also provided with a coin opening or socket 7, of a diameter equal to the coin which it is intended to discharge. These coin-ejecting plates 6 may be in vertical series one above the other, depending upon 70 the number of coins that it is desired to eject at one time, and each plate is provided with an aperture 8, designed to receive one end of a spring-actuating rod 9, secured, preferably, to the back of the casing. 75

Each plate except the bottom one is provided with a recess 10 for the passage therethrough of the rods 9, so that, for instance, by actuating the rod 9, secured to the lowermost plate, only that plate will be drawn to 80 eject a single coin, and in like manner one, two, three, four, or any desired number of the plates may be simultaneously drawn, the recess of each plate supplying a clearance for the actuating-rods of the plates below it. 85 For each rod there is a corresponding actuating-lever, which in this instance is designated 11. Each lever is fulcrumed on the back of the casing and is provided with two arms, one of which engages one or more of 90 the rods 9 and the other of which is provided with the proper designating key or finger-piece. As a concrete example, let it be assumed that the apparatus here illustrated is both a coin-delivering apparatus and also an 95 apparatus for subtracting automatically any amount to give the required change from a given bill without the operator having to compute the same.

At the left hand of the apparatus there is 100 arranged a coin-cup for silver dollars. In order to give the proper amount in change from a five-dollar bill, I have arranged below the main discharge end of said cup 5 ejecting-plates one above the other, to each of which 105 is secured one of the actuating-rods 9 and for the operating of which there are provided four levers. Each of the keys or finger-pieces of these levers display two characters and for the purpose of distinguishing the meaning of the characters of each key the upper character of each key is an Arabic nu- 110

meral, while beneath it is Roman. In this instance it will be seen that one key contains the characters $\frac{1}{IV}$. Another contains the characters $\frac{2}{III}$. Another contains the characters $\frac{3}{II}$; another, $\frac{4}{I}$. Now if a one-dollar sale has been made and the purchaser hands the dealer a five-dollar bill, all the latter has to do is to press down the key marked $\frac{4}{I}$, which will designate the purchase, and the lever to which said key is connected being actuated will in turn swing all four of the rods secured to the coin-ejecting plates beneath the one-dollar cup, and thereupon all four of the one-dollar coin-plates will be drawn and proper change will be automatically discharged into the chute 3. On the other hand, if the sale has amounted to four dollars and a five-dollar bill is handed the dealer the latter will press down the key marked $\frac{1}{IV}$, when only the lowermost plate of that cup will be drawn and only one coin will be discharged into the chute.

It is obvious that various and almost unlimited combinations may be made by my invention, only depending upon the number of coin-ejecting plates superposed, as described, and, furthermore, if it is desired to make change automatically to subtract any odd amount—such, for instance, as to make one dollar and fifty-one cents change—it will be only necessary for the operator to press the proper keys. It is preferred to have the twenty-five-cent-column and the five-cent column operate singly, because these amounts are so frequently in demand in making change.

It is to be understood that the coins are dropped through openings in the plate 12 when the coins are moved rearwardly by ejecting-plates, so as to allow one or more of the coins to drop into the chute 3.

Having thus described the invention, what is claimed as new is—

1. A device of the character described comprising cups for coins of different denominations, coin-ejecting plates arranged in superposed series of predetermined number and

each arranged to eject a single coin from its respective cup, an operating-rod secured to each of said plates, and the latter provided with recesses as described for the clearance of said rods, and operating-levers arranged to actuate one or more of said rods at a time.

2. In a device of the character described, a series of cups for coins of different denominations, a predetermined number of coin-ejecting plates, set one above the other in said cups and each arranged to eject therefrom a single coin, each of said plates being provided with an aperture 8, and all but the bottom plate being provided with a recess, operating-rods passing down through said recesses and each secured to one of the plates, and means for actuating any number of said rods at a time.

3. A device of the character described, comprising a coin-receiving cup, a predetermined number of coin-ejecting plates arranged one above the other in the bottom of said cup and each arranged to eject a single coin therefrom, each of said plates but the bottom plate being provided with a recess, the recesses being of different sizes, operating-rods passing down through said recesses and each secured to one of the plates, and levers arranged to actuate one or more of said rods at a time.

4. A device of the character described, comprising a series of cups designed to contain coins of different denominations, a predetermined number of coin-ejecting plates mounted one upon the other in the bottoms of said cups and each arranged to eject therefrom a single coin, each of said plates, except the bottom plate, being provided with a recess, and the said recesses of the respective plates increasing in width toward the uppermost plate, spring-operating rods secured to the respective plates and passing down through the clearance provided by said recesses, and a series of levers provided with arms arranged to respectively actuate one or more of said rods at a time.

In testimony whereof I affix my signature in presence of two witnesses.
